Primary Examiner — Ramzi S Almatrahi(74) *Attorney, Agent, or Firm* — Intellent Patents LLC; Ahmed Alhafidh(57) **CLAIM**

The ornamental design for a rescue search camera, as shown and described.

DESCRIPTION

FIG. 1 is a front perspective view of a rescue search camera showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top plan view thereof, shown in condition of use and mounted with a telescoping pole disclosed in broken lines to illustrate an environment.

The broken lines showing a telescoping pole in FIG. 8 represent environmental structure that form no part of the claimed design.
